UNITED STATES PATENT OFFICE.

JOHN C. GRIFFIN, OF PHILADELPHIA, PENNSYLVANIA.

DESIGN FOR A RUG.

SPECIFICATION forming part of Design No. 17,005, dated November 30, 1886.

Application filed October 2, 1886. Serial No. 215,194. Term of patent 3½ years.

To all whom it may concern:

Be it known that I, JOHN C. GRIFFIN, a citizen of the United States, and a resident of Philadelphia, in the county of Philadelphia and State of Pennsylvania, have invented and produced a new and useful Design for a Rug, of which the following is a specification, reference being had to the accompanying photograph, forming part thereof.

10 In the center of the rug is a center piece, A, surrounded by thirteen stars, B, representing the thirteen original States of the Union. These stars are surrounded by thirty-eight stars, C, representing the thirty-eight States 15 as now constituted, and these stars are surrounded by the border D. Upon each side of the center piece is a panel containing a stack of arms, E, a camp-stool, F, and tents G in the background.

I claim—

20 The design for a rug, consisting of the center piece, A, surrounded by thirteen stars, B, which are surrounded by thirty-eight stars, C, the whole being inclosed by the border D, and having at each end a panel containing a stack of 25 arms, E, a camp-stool, F, and tents G, all substantially as set forth.

JOHN C. GRIFFIN.
